UNITED STATES PATENT OFFICE.

FREDRICK B. ADAM, OF ST. LOUIS, MISSOURI, ASSIGNOR TO FRANK ADAM ELECTRIC COMPANY, OF ST. LOUIS, MISSOURI, A CORPORATION OF MISSOURI.

KNIFE-BLADE SWITCH.

1,299,891.

Specification of Letters Patent. Patented Apr. 8, 1919.

Application filed April 23, 1918. Serial No. 231,370.

To all whom it may concern:

Be it known that I, FREDRICK B. ADAM, a citizen of the United States, residing at St. Louis, Missouri, have invented a certain new and useful Improvement in Knife-Blade Switches, of which the following is a full, clear, and exact description, such as will enable others skilled in the art to which it appertains to make and use the same.

10 This invention relates to knife blade switches, and has for its main object to provide a knife blade switch that can be manufactured at a low cost, that is strong and substantial and which presents a neat and finished appearance. Another object is to provide a novel method of making a knife blade switch.

To this end I have devised a knife blade switch in which the blade is connected to the cross bar or handle by a screw, bolt or similar fastening device that is tapped into an integral socket in the handle end of the blade formed by laterally-expanded portions of the blade. I have also devised a novel 25 method of making said switch which is characterized by forcing a punch into the end of the blade and expanding the metal in the blade laterally intermediate the edges of the blade, so as to form the socket which receives the device that connects the blade to the cross bar or handle of the switch.

Figure 1 of the drawings is a top plan view of my improved switch.

Fig. 2 is a side elevational view of the 35 switch.

Fig. 3 is a perspective view, illustrating one form of my invention; and

Fig. 4 is a perspective view, illustrating another form of my invention.

40 Referring to the drawings, A designates the blades of my improved switch which are connected in any preferred manner to hinge standards 1, and B designates the cross bar to which the free ends of the blades A are connected. In a single pole switch the blade is connected directly to the handle instead of to a cross bar. The cross bar B is connected to the blades A by screws 2 that pass through the cross bar and are screwed into 45 internally screw-threaded integral sockets 3 on the blades, each blade being connected to the cross bar by a separate screw.

The socket 3 on each blade is formed by forcing a punch or other suitable device into

the end of the blade and expanding the 55 metal in the blade laterally into a die in which the end portion of the blade is confined, thereby producing a longitudinally-disposed socket in the end portion of the blade whose side walls project laterally from 60 the blade, the side walls of said socket 3 being of about one-half the thickness of the blade, as shown in Fig. 3.

After the metal in the end portion of the blade has been expanded laterally in the 65 manner above described to form the socket 3, a tap is run into said socket so as to form screw threads 3^a on the interior of same to receive the threads on the screw 2. The cross bar B is provided with a transversely-disposed groove 4 that receives the end portion of the blade A, and said groove is provided intermediate its ends with an enlarged portion 4^a that receives the end portion of the socket 3 on the blade. 75

While I prefer to have the end of the socket 3 terminate flush with the end of the blade, as shown in Fig. 3, this is not essential, for if desired, the blade can be provided with a socket 13, as shown in Fig. 4, 80 whose end terminates some distance inwardly from the end of the blade. When the blade is formed in the manner shown in Fig. 4 the cross bar B is merely provided with a transversely-disposed slot 14 into 85 which the projecting end portion of the blade extends, the end of the socket 13 butting against the flat underside of the cross bar.

By constructing a knife blade switch in 90 the manner above described I am able to manufacture the switch at a very low cost, owing to the fact that the blade is connected to the cross bar or handle by a screw which is screwed directly into the end of the blade 95 instead of into a nut or separate part carried by the blade, the portion of the blade that receives said screw being formed by expanding the metal in the end portion of the blade laterally by means of a punch that is 100 forced into the end of the blade, so as to divide the metal and force it laterally in opposite directions at a point intermediate the edges of the blade. No upsetting operation is required to increase the thickness of 105 the end portion of the blade, nor is it necessary to use a longer blade or a thicker blade than the blade of a standard knife switch.

While the side walls of the socket 3 are approximately only one-half the thickness of the blade, nevertheless, said socket contains sufficient metal to insure a strong and substantial fastening means for the screw 2. The end of the blade is set into the cross bar, or into the handle, in the case of a single pole switch, in such a manner that it is impossible for the blade to twist or turn relatively to the cross bar, consequently, the only work the screw 2 has to do is to prevent the blade from pulling away from the cross bar. The socket 3 on the blade is so small and compact that the switch presents a neat and finished appearance, and another desirable feature that results from connecting the blade and the cross bar together in this manner is that it permits a number of blades to be arranged close together in a multiple blade switch without the necessity of using a cumbersome head into which the blades are milled and riveted, as has heretofore been the usual practice in multiple blade switches.

Having thus described my invention, what I claim, and desire to secure by Letters Patent, is:

1. A knife blade switch, comprising a blade provided at its handle end with laterally-expanded portions that extend longitudinally of the blade intermediate the edges of the blade, a cross bar or handle, and a screw or similar device extending through the cross bar or handle and tapped into said laterally-expanded portions.
2. A knife blade switch, comprising a blade provided at its handle end with a longitudinally-disposed socket whose diameter is greater than the thickness of the blade and whose side walls consist of laterally-expanded portions of the blade which are substantially one-half the thickness of the metal in the blade, a cross bar or handle provided with a slot for receiving the end portion of the blade, and a screw-threaded

connecting device for said elements tapped into the socket in said blade.

3. A knife blade switch, comprising a blade provided at its handle end with laterally-expanded portions that extend longitudinally of the blade intermediate the edges of the blade and whose outer ends terminate some distance inwardly from the end of the blade, a cross bar or handle butting against the ends of said laterally-expanded portions and provided with a slot for receiving the end portion of the blade, and a screw or similar device extending through the cross bar or handle and tapped into the laterally-expanded portions of the blade.

4. A method of making a knife blade switch, characterized by dividing the metal in the handle end of the blade and expanding it laterally in opposite directions at a point intermediate the edges of the blade so as to form a longitudinally-disposed socket in the end of the blade, forming screw threads in said socket, and thereafter connecting a cross bar or handle to the blade by means of a screw or other suitable device that is screwed into said socket.

5. A method of making a knife blade switch, characterized by arranging the handle end of the switch blade in a die, forcing a punch or other suitable device into the end of the blade so as to expand the metal in the blade laterally into said die, thereby producing a longitudinally-disposed socket in the end of the blade whose side walls are approximately one-half the thickness of the metal in the blade, running a tap into said socket so as to form screw threads on the interior of same, arranging the end portion of the blade into a slot in a cross bar or handle, and connecting said cross bar or handle to the blade by means of a screw or similar device that is screwed into the socket in the blade.

FEDRICK B. ADAM.
